UNITED STATES PATENT OFFICE.

GEORGE K. RIX, OF CHICAGO, ILLINOIS, ASSIGNOR TO THE YAWMAN & ERBE MANUFACTURING COMPANY, OF ROCHESTER, NEW YORK.

DESIGN FOR A BASKET.

SPECIFICATION forming part of Design No. 33,268, dated September 25, 1900.

Application filed August 28, 1900. Serial No. 28,361. Term of patent 14 years.

To all whom it may concern:

Be it known that I, GEORGE K. RIX, a citizen of the United States, residing in the city of Chicago, county of Cook, and State of Illinois, have invented and produced a new and original Design for a Letter-Basket, of which the following is a specification, reference being had to the accompanying drawing, forming a part thereof.

The drawing shows in perspective a basket or receptacle embodying my design.

The design consists of the basket or recep-

tacle of woven filamentous material, as wire, having one side 1 and the ends 2 extending at an angle to the bottom 3. The side 1 and bottom 3 are cut away, as shown, at or near the center to form the hand-hole or recess 4.

I claim—

The design for a basket substantially as herein shown and described.

GEORGE K. RIX.
